(57) **CLAIM**

The ornamental design for a center console for automobile, as shown and described.

DESCRIPTION

1. Center console for automobile

1.1 : Perspective

1.2 : Front

1.3 : Back

1.4 : Left

1.5 : Top

1.6 : Bottom

1.7 : Reference photo

The broken lines depict portions of the center console for automobile that form no part of the claimed design. The dash-dot broken lines define the boundary of the claimed design and form no part thereof. FIG. 1.7 shows the claimed design in use. The material surrounding the claimed design, as disclosed in figures 1.1-1.6, depicts unclaimed environmental subject matter.
